SANITARY ATTACHMENT FOR DISINFECTING TELEPHONE MOUTHPIECES

Roy L. Lewis, Decatur, Ga.

Application July 9, 1948, Serial No. 37,856

7 Claims. (Cl. 179—185)

1

This invention relates to telephone transmitters and is particularly directed to improving the sanitary properties thereof through the use of replaceable filters in conjunction with the mouthpiece of telephone transmitters.

It has heretofore been proposed to provide various types of attachment mounting removable discs of filter paper or equivalent filter elements for use in conjunction with telephone transmitter mouthpieces. According to the present invention a special form of filter element is provided for mounting on the mouthpiece itself. Additionally, the transmitter mouthpiece may be modified from conventional constructions to reliably secure removably replaceable filter elements on the mouthpiece.

The invention will be more fully understood by reference to the illustrative embodiment thereof in the accompanying drawing.

In such drawing,

Fig. 1 is a vertical cross-sectional view of a device embodying the invention;

Fig. 2 is a side view, partly in section and partly in elevation, corresponding to Fig. 1;

Fig. 3 is a fragmentary cross section taken on line 3—3 of Fig. 2;

Fig. 4 is a rear view of a filter element; and,

Fig. 5 is a side view, partly in section, of the filter element shown in Fig. 4.

A telephone transmitter mouthpiece cap is shown in Figs. 1 to 3, comprising an annular body portion 10 having an internally threaded flange 11 at its rear end and mounted on a telephone transmitter such as indicated at 12. Such body portion surrounds a central apertured voice transmitting area. Such area may be entirely open, or, as shown, include a relatively thin portion 13 integral with body 10 and having a multiplicity of voice perforations 14. Portion 13 is located somewhat inwardly from the outer end of annular body 10. The mouthpiece and cap so far described are conventional.

The special filter element of the invention is best shown in Figs. 4 and 5. The same comprises a circular disc 15 having a rearwardly extending peripheral flange 16. Flange 16 is of an internal diameter such as to closely fit the outer periphery of the annular body portion 10 of the mouthpiece cap adjacent to its outer end. Preferably also, flange 16 meets disc 15 of the filter element in a curve conforming to the usual curve between the outer periphery and outer end of the mouthpiece body portion.

The filter element should be of paper or other material having voice transmitting properties or if other material is employed, multiple perfora-

tions, not shown, similar to perforations 14 in mouthpiece portion 13 may be provided.

By making flange 16 of the filter element relatively stiff and of sufficient depth the element 5 may be removably supported on the mouthpiece and in covering relations with the voice transmitting central area merely through frictional engagement of flange 16 with the outer periphery of the mouthpiece body portion 10. However, for 10 reliability of mounting and particularly, where, as shown, the mouthpiece periphery tapers rearwardly, it is desirable to provide retaining means for holding the filter element flange in position on the mouthpiece. In its preferred form such 15 retaining means includes an annular groove in the outer periphery in the mouthpiece body portion 10 at or about the plane of maximum diameter of the mouthpiece. Coaxial with such groove is a retaining ring 18 having maximum 20 diameter the same as or slightly larger than the maximum diameter of the mouthpiece. Ring 18 is constructed of resilient metal and while having a generally circular shape it is provided with resilient flattened side portions 19. Between the 25 opposing side portions 19 the ring is reduced in diameter to the diameter of groove 17, as will be understood from Fig. 2, so that flange 16 of the filter element is pressed into groove 17, at recurrent circumferential points and held in gripping engagement by side portions 19 of the ring. Because of the resilient character of ring 18 it 30 will expand in diameter at side portions 19 to permit ready application to and removal from the mouthpiece of both the ring and the filter element.

For convenience retaining ring 18 may be 35 mounted on the mouthpiece as by a hinge 20 anchored in the mouthpiece body 10 rearwardly of groove 17 and connecting with a rearwardly offset portion 21 formed on the ring.

One advantage of providing the retaining means 40 is that the supply of the flange filter elements becomes exhausted. Flat sheet tissue paper or other material which is not too stiff can be employed as a filter element by cutting the same to a size somewhat larger than the diameter of the mouthpiece and bringing the margin thereof against the periphery of the mouthpiece. The retaining ring will coact with groove 17 to hold 45 the margin at the recurrent flanged ring side portions 19. Even though other areas of the filter paper margin are not positively gripped the entire circumference of the margin is embraced by the ring and a satisfactory mounting on the 50 mouthpiece is obtained.

The mounting of a filter element on the outer

end of a telephone transmitter mouthpiece not only provides a simple construction but gives sanitary protection to the outer end of the annular body portion of the mouthpiece as well as to the voice transmitting central area. Where, as preferred, retaining means are provided to insure against falling off of a filter element when the telephone transmitter is in use such retaining means may include a simple resilient ring embracing the mouthpiece which is hardly noticeable and which does not interfere with the use of the telephone transmitter.

As has previously been pointed out the filter element retaining means and the particular form of filter element shown in Figs. 4 and 5 may be employed apart from each other as well as in combination. The scope of the invention is to be adjudged from the appended claims.

I claim:

1. A sanitary unit for telephone transmitters comprising a transmitter mouthpiece cap having an annular body portion surrounding an apertured central area, a removable filter disc mounted on the outer end of the annular body portion and having a peripheral supporting flange extending laterally therefrom and snugly embracing the outer periphery of the annular body portion and retaining means detachably securing the filter disc flange in position on the outer periphery at the annular body portion.

2. A sanitary unit for telephone transmitters comprising a transmitter mouthpiece cap having an annular body portion surrounding an apertured central area, a removable filter disc mounted on the outer end of the annular body portion and having a peripheral supporting flange surrounding the outer periphery of the annular body portion and a removable expandable ring surrounding the filter disc flange and securing the flange in gripping engagement with the outer periphery of the annular body portions.

3. A sanitary unit for telephone transmitters comprising a transmitter mouthpiece cap having an annular body portion surrounding an apertured central area, a removable filter disc mounted on the outer end of the annular body portion and having a peripheral supporting flange surrounding the outer periphery of the annular body portion, a removable retaining ring surrounding the filter disc flange and coactive with annular body portion to secure the flange in position and hinge means secured to the annular body portion and mounting the retaining ring for swinging movement outwardly over the outer end of the annular body portion.

4. A sanitary unit for telephone transmitters comprising a transmitter mouthpiece cap having an annular body portion surrounding an apertured central area, a removable filter disc mounted on the outer end of the annular body portion and having a peripheral supporting flange surrounding the outer periphery of the annular body portion, a circumferential groove in the outer periphery of the annular body portion

underlying the filter disc flange and a removable resilient ring surrounding the flange at the plane of the groove and coactive with the groove to anchor the flange in position on the annular body portion.

5. A sanitary unit for telephone transmitters comprising a transmitter mouthpiece cap having an annular body portion surrounding an apertured central area, a removable filter disc mounted on the outer end of the annular body portion and having a peripheral supporting flange surrounding the outer periphery of the annular body portion, a circumferential groove in the outer periphery of the annular body portion underlying the filter disc flange, a resilient retaining ring surrounding the flange and coactive with the groove to anchor the flange in position on the annular body portion and hinge means secured to the annular body portion mounting the ring in the plane of the groove and for swinging movement outwardly over the end of the annular body portion.

6. A mouthpiece cap for telephone transmitters for use with a filter element comprising an annular body portion surrounding an apertured central area and having an outer end provided with means for seating a filter element, a removable retaining ring surrounding the outer periphery of the annular body portion and having means for clamping a filter element to the outer periphery of the annular body portion and hinge means secured to the annular body portion and mounting the retaining ring for outward swinging movement over the end of the annular body portion.

7. A mouthpiece cap for telephone transmitters for use with a filter element comprising an annular body portion surrounding an apertured central area and having an outer end provided with means for seating a filter element, a circumferential groove in the outer periphery of the annular body portion and a removable resilient retaining ring surrounding the annular body portion and being coactive with the groove to clamp a filter element to the outer periphery of the annular body portion.
